UNITED STATES PATENT OFFICE.

HOWARD W. JUDSON, OF LONG BEACH, AND HERBERT A. LOWMAN, OF WILMINGTON, CALIFORNIA, ASSIGNEES OF ONE-HALF TO SEA PRODUCTS COMPANY, OF LONG BEACH, CALIFORNIA, A CORPORATION OF CALIFORNIA.

KELP-INCINERATOR.

1,259,457.

Specification of Letters Patent.

Patented Mar. 12, 1918.

Application filed December 1, 1916. Serial No. 137,590.

To all whom it may concern:

Be it known that we, HOWARD W. JUDSON and HERBERT A. LOWMAN, citizens of the United States, residing at Long Beach and 5 Wilmington, respectively, in the county of Los Angeles and State of California, have invented new and useful Improvements in Kelp-Incinerators, of which the following a specification.

10 This invention relates to an apparatus for burning kelp to ashes.

It is the principal object of this invention to provide a furnace within which kelp may be reduced to kelp ash in a rapid and 15 thorough manner.

Another object of this invention is to provide means whereby a large quantity of kelp may be subjected to the flames of a burner at a single time and will thereby increase 20 the production over that of most furnaces now in use.

Another object of this invention is to provide a kelp furnace which may be heavily fed and which is not liable to be 25 come choked.

Another object of this invention is to provide a series of kelp receiving bars within a kelp incinerating furnace which will insure that the flame from the furnace burner 30 will act equally upon all of the kelp within the furnace and thereby produce a high grade ash.

Another object is to provide a means of incinerating kelp which will uniformly reduce it to an ash of commercial value and 35 in a rapid manner.

It is a further object of this invention to provide an apparatus for incinerating kelp which is simple and effective and may be 40 operated continuously without necessity of closing down for repairs or in order to remove the ash.

Other objects will appear hereinafter.

The invention is illustrated, by way of 45 example, in the accompanying drawings, in which:

Figure 1 is a view in vertical transverse section as seen through the preferred form of furnace construction.

50 Fig. 2 is a view in section and plan as seen on the line 2-2 of Fig. 1 and illustrates the staggered arrangement of the furnace kelp receiving bars.

Referring more particularly to the draw-

ings, 10 indicates a furnace shell which is 55 provided with a bottom 11 and a top 12. The shell and bottom are lined with a heat insulating lining 13, while the top is here shown as formed with a flue opening 14 and a charging opening 15 through which the 60 kelp may be fed to the furnace. The charging opening is fitted with a door 16.

Referring particularly to Figs. 1 and 2 of the drawings it will be seen that the furnace here disclosed is provided with a series 65 of horizontally extending kelp receiving bars 17. These bars are of various lengths and are staggered in relation to each other as they extend radially from the inner wall of the furnace. Positioned beneath the bars 70 and adapted to supply heat and flame to the furnace is a suitable oil burner 18. It is evident, however, that other types of burners might be used with success. This burner is provided with an oil feed pipe 19 and an 75 air pressure pipe 20. The shell of the furnace is formed with one side opening 21 through which the ash may be removed. This opening is fitted with a hinged door 22 by which it may be closed when desired. 80

In the operation of the invention the kelp is fed into the furnace through charging opening 15 where it will become lodged upon the various radially disposed bars and will be distributed through the interior of 85 the furnace. The burner 18 will be in operation and will produce a sufficient degree of heat to reduce the kelp to ash. It is evident that, due to the staggered and irregular arrangement of the kelp receiving bars, the 90 lengths of kelp will be festooned upon the bars and will so remain until they have become charred and have fallen to the bottom of the furnace as ash.

It will thus be seen that the apparatus 95 for incinerating kelp for the purpose of reducing it to ash, as here disclosed, involves the use of a simple furnace construction and insures that the incineration process will be rapid and that large quantities of 100 the kelp may be fed into the furnace without danger of retarding the action of the burner.

While we have shown the preferred construction of our kelp incinerator, it will be 105 understood that various changes in the combination, construction and arrangement of parts may be made by those skilled in the

art without departing from the spirit of
our invention.

We claim:

A furnace adapted for burning large
5 quantities of kelp and comprising a vertically
arranged cylindrical shell provided
with a flat bottom and an outlet door im-
mediately above the bottom, a top for the
shell forming a flue and a charging open-
10 ing; the flue being at one side and the
charging opening being large enough to re-
ceive kelp from a pitch-fork; a cover for
the charging opening, a burner mounted
same distance above the bottom of the shell
15 and co-axially therewith, and kelp receiv-
ing bars extending horizontally and radi-

ally inwardly from the shell toward the
center and in staggered relation to each
other; said bars being of different lengths,
each extending only part way across the 20
shell, and arranged from the level of the
burner upwardly to the top of the shell; so
that kelp may be pitch-forked through the
charging opening to the bars and so that
the ashes may be removed from the bottom 25
below the bars through the door below the
burner.

In testimony whereof we have signed our
names to this specification.

HOWARD W. JUDSON.
HERBERT A. LOWMAN.
